UNITED STATES PATENT OFFICE.

GEORGE A. BURKHOLDER, OF SHOAL LAKE, MANITOBA, CANADA.

AUTOMOBILE VENTILATOR.

Application filed June 28, 1926. Serial No. 119,110.

The present invention relates to improvements in ventilators, and has reference more particularly to a ventilator construction primarily for use in conjunction with the top of 5 limousines, sedans, coupes or other types of closed automobiles.

One of the important objects of the present invention is to provide a ventilator of the above mentioned character which may be 10 readily and easily adjusted to secure the desired amount of circulation of air in the closed automobile.

A further object of the invention is to provide a ventilator of the above mentioned 15 character, which is simple in construction, inexpensive, strong and durable, and further well adapted for the purposes for which it is designed.

Other objects and advantages of this invention will become apparent from the following description.

In the accompanying drawing forming a part of this specification, and in which like numerals designate like parts throughout the 25 same:

Figure 1 is a bottom plan view of the ventilator constructed in accordance with the present invention, the same being shown arranged in the ceiling or top of a closed vehicle.

Figure 2 is a detail vertical sectional view thereof, parts being shown in side elevation.

Figure 3 is a detail view of the connection between the hinged lid and the actuating 35 rod, and

Figure 4 is a detail sectional view of the spider and the adjacent portion of the actuating rod.

In the drawings, wherein for the purpose 40 of illustration is shown the preferred embodiment of my invention, the numeral 5 designates the crown wall or ceiling of a closed body automobile, the same being formed at a desirable point with a rectangular shaped opening 6.

Rigidly disposed within this opening is my improved ventilator, the same comprising a substantially rectangular shaped metallic frame or shell 7. This frame is open 50 at its top and bottom, and is formed intermediate the top and bottom thereof with the spaced horizontal spiders 8, the central webs 9 of which are formed with registering openings 10, through which is slidable a vertical 55 rod 11.

Hingedly secured at 12 to the forward

edge of the frame or shell 7 is a closure lid 13 for the open top of the frame. The hinged connection includes axial coil springs 13' that normally act to maintain the lid in 60 a closed position with respect to the frame. As is clearly shown in Figure 2, the upper edge portion of the frame or shell 7 extends above the top surface of the ceiling 5 and a depending flange 14 is associated with the 65 closure lid for engagement with the upper edge portion of the frame or shell. A laterally extending flange 15 is formed on the lower edges of the frame for engagement with the bottom face of the ceiling in the 70 manner as clearly shown at 15 in Figures 1 and 2.

The upper end of the rod 11 is bifurcated as illustrated at 16, with reference more particularly to Figure 3. A pair of spaced 75 ears 17 depend from the intermediate portion of the bottom of the closure lid 13. A connecting link 18 is pivotally secured at its upper end between the spaced ears 17 as at 19, the lower end of said link being pivotally 80 supported in the bifurcated upper end 16 of the vertical rod 11 as at 20. In this manner, an operative connection between the upper end of the vertical rod and the closure lid 13 is provided, and the purpose thereof will be 85 hereinafter more fully described.

A cross bar 21 extends transversely across the bottom portion of the frame or shell 7, and the same is provided with an opening 22 in the central thickened portion 23 thereof. 90 A rod 24 extends through this opening 22, the upper portion of the rod being threaded as illustrated at 25 for cooperation with the threaded socket 26 provided in the lower end of the vertical rod 11, which rod 11 is of 95 a greater diameter than the rod 24.

A knurled hand wheel 27 is provided on the lower end of the rod 24 to facilitate the actuation of said rod and for the purpose of providing the vertical movement of the 100 rod 24, I provide the intermediate portion of the rod with the spaced stop collars 28 and 29, respectively. The collar 28 is adapted to engage the upper face of the thickened portion 23 of the cross bar 21, while the 105 collar 29 engages the bottom face of the central thickened portion 23 in the manner as clearly shown in Figure 4. These stop collars may be secured on the rod 24 in any suitable manner.

It is obvious that when the thumb wheel 110 27 is turned in one direction, the rod 24 will

be rotated causing the threaded upper end 25 to cooperate with the threaded socket 26 provided in the lower end of the rod 11 in raising the rod upwardly and simultaneously raising the lid 13 to an open position so that the desired circulation of air through the opening 6 in the ceiling of the car may be obtained. Manifestly by turning the rod 24 in the reverse direction, the 10 rod 11 will be lowered, thus moving the closure lid 13 to a closed position and the actual coil springs 13 will cooperate in maintaining the lid in its closed position.

The purpose of the link 18 is to provide 15 a means whereby the rod 11 will move vertically, upwardly and downwardly and permit the positive swinging movement of the closure lid 13. Arranged within the frame 7 is a moisture collecting trough or gutter 20 30 and associated with the same is the discharge pipe 31.

It will thus be seen from the foregoing description, that I have provided a highly novel yet simple and efficient ventilator for 25 closed types of automobiles, which may be readily and easily installed without necessitating any material alterations and the simplicity of my improved ventilator enables the same to be readily and easily actuated. 30 While I have shown the preferred embodiment of my invention, it is to be understood that various changes in the size, shape and arrangement of parts may be resorted

to without departing from the spirit and sacrificing any of the advantages of the 35 appended claims.

Having thus described the invention, what I claim is:

In a closure operator mechanism of the class described, a frame open at its top and 40 bottom, a lid hingedly secured to the top of the frame to provide a closure therefor, spaced horizontal spiders arranged within the frame, the web portions of said spiders being provided with registering openings, 45 a rod adapted for vertical slidable movement through said openings, a link affording the pivotal connection between the upper end of the rod and the intermediate portion of the bottom of said lid, means whereby 50 the rod may be raised or lowered for actuating the lid, said means comprising a threaded rod, the lower end of the first mentioned rod having a threaded socket formed 55 therein for cooperation with the upper threaded end of the last mentioned rod, a cross bar through which the threaded rod extends, a handle supported on the lower end of the threaded rod for actuating the same, and stop collars secured on the threaded rod and arranged on opposite sides of the cross bar for preventing the vertical movement of said threaded rod.

In testimony whereof I affix my signature.

GEORGE A. BURKHOLDER.
